ZIPPER KIT**Edward J. Voit, 141 Bellmore Road,
East Meadow, N.Y. 11554****Continuation-in-part of application Ser. No. 556,350,
June 9, 1966. This application Sept. 9, 1966, Ser.
No. 592,707****Int. Cl. A44b 19/34****U.S. CL. 24—205.11****6 Claims****ABSTRACT OF THE DISCLOSURE**

A slide fastener wherein an end stop is formed by folding and adhesively securing the tape ends at an angle. The tapes also include an adhesive release tape positioned along the fastener tape. When the release tape is peeled off, the adhesive is left on the fastener tapes to be used for attaching to clothing.

This application is a continuation-in-part of copending application Ser. No. 556,350 filed June 9, 1966, now abandoned.

This invention relates generally to a zipper kit whereby zippers of a single length or a plurality of lengths may be prepackaged with suitable adhering material in order that the consumer may utilize a selected zipper and the adhering material to fabricate a zipper of substantially any required length. The invention is further directed to the utilization of adhering material supplied in the form of transfer tape whereby the adhering material may be utilized to baste or temporarily attach the zipper to the garment to simplify the installation of zippers in garments or other types of articles having zipper closures. The invention is also directed to an arrangement for shortening a prefabricated zipper without the use of special tools or equipment.

One of the largest groups of zipper users is the consumer who purchase zippers from variety and department stores for use as replacements and for garments made at home. The latter use is ever increasing as a result of the increasing variety of patterns available for the home seamstress as well as a substantial increase in the market of moderate price sewing machines of good quality. Many garments require a zipper closure and thus variety and department stores generally stock zippers of various lengths. The length of a zipper installed in a garment must be properly selected in accordance with the construction of the garment in order for it to operate properly. Thus, the home seamstress usually must purchase the exact size zipper required for each application thereby making it substantially impracticable to keep on hand a small stock of zippers since it is generally impossible to predict in advance the length of zipper that may be required.

While a substantial number of zippers are purchased by the home seamstress, the installation of same has always been considered difficult due to the accuracy required in initial placement and basting of the zipper prior to the final sewing operation.

Accordingly, it is an object of this invention to provide a zipper kit which will include zippers having lengths at least as great as the anticipated need together with means for shortening the zipper to the length required for any particular application.

Another object of the invention is to provide means for shortening a prefabricated zipper without the use of special tools or equipment.

A further object of the invention is to provide means for temporarily adhering a zipper to a garment for the

2

final stitching operation thereby eliminating the baste stitch operation.

Still other objects and advantages of the invention will in part be obvious and will in part be apparent from the specification.

Generally speaking, in accordance with an embodiment of the invention, one or more zippers are prepackaged in a kit with a zipper tape adhering material. The zippers are intentionally longer or as long as the required length for expected applications with various length ranges being made available in various kits. The zipper tape adhering material may be in the form of a pressure sensitive or heat sensitive tape or an adhesive to secure the zipper tape in a folded position to thereby shorten the effective length of the zipper and provide a slider stop at the upper end thereof. The zipper tape adhering material may also be in the form of transfer tape which may be used to transfer a length of adhesive to each of the zipper tapes by which the zipper may be temporarily adhered to the garment for the final stitching operation.

The invention accordingly comprises the features of construction, combination of elements, and arrangement of parts which will be exemplified in the construction hereinabove set forth, and the scope of the invention will be indicated in the claims.

For a fuller understanding of the invention, reference is had to the following description taken in connection with the accompanying drawing, in which:

FIG. 1 is a perspective view of a zipper kit packaging several zippers together with zipper tape adhering material;

FIG. 2 is a plan view of a zipper longer than required for a particular application being trimmed to size;

FIG. 3 is a plan view of the rear side of a trimmed zipper with zipper tape adhering material applied to the zipper tape proximate to the upper end thereof;

FIG. 4 is a side elevational view of the zipper of FIG. 3 with the upper ends of the zipper tape folded and adhered to form a zipper of desired length;

FIG. 5 is a partial plan view, at enlarged scale, of a portion of zipper tape fabricated to form a slide stop;

FIG. 6 is a plan view of the front side of a zipper with transfer tape adhered to the zipper tapes;

FIG. 7 is a sectional view taken along line 7—7 of FIG. 6;

FIG. 8 is a partial plan view of the front side of the zipper of FIG. 6 with the release paper of the transfer tape removed and with the zipper shortened in accordance with the teachings of the invention; and

FIG. 9 is a perspective view of a roll of transfer tape.

Referring to FIG. 1, a kit 11 consists of a package including a plurality of zippers 12 and zipper tape adhering material 13. Zippers 12 may be of the same length or various lengths with the length being as long as or longer than required for the expected use. For example, the kit may contain two jacket zippers 23" long, two dress zippers 22" long and two skirt or slack zippers 10" long. With such a kit, the home seamstress would have immediately available zippers for substantially every possible application with the length of the zipper for a particular application being as long as or longer than normally required for such application. Thus, the dress zipper, for example, could be used for any dress requiring a zipper up to 22" long with the correct length being under control of the seamstress as will be hereinafter described.

The zipper tape adhering material may be in the form of any suitable material which will adhere the zipper tape in folded over position as will also be hereinafter described. The zipper tape adhering material may, for example, take the form of a double sided pressure sensitive tape, a heat sealable vinyl tape, a transfer tape or a spreadable adhesive.

Referring to FIGS. 2 through 5, a typical zipper 12 is shown consisting of tape sections 14, teeth 15, a bottom stop 16, top stops 17 and a slider 18.

Assuming, by way of example, that zipper 12 is a dress zipper having a length of 22" and a dress zipper having a length of only 14" is required, the top portion of the zipper will be cut off by the seamstress using scissors 19. The zipper would be cut to a length of 14½" to provide a fold over of ½" on each tape for formation of the top stops to replace top stops 17 which were discarded when the top half of the zipper was cut off.

Referring to FIG. 3, zipper tape adhering material 13 is applied to the rear of each tape section for the length of the tape over and above its required length. In the particular example, the zipper was cut ½" longer than required and thus the zipper tape adhering material is applied to each tape section for a length of ½".

Referring to FIGS. 4 and 5, the extra half inch of each tape section is folded on itself as at 21 to thereby form a zipper of required length. As shown in FIG. 5, the tape is folded at a slight angle from its longitudinal axis to prevent overlap of teeth 15 to prevent undue bulkiness and interference with the sliding action of slider 18 at the top end of the zipper. When folded over, the tape is adhered to itself by the zipper tape adhering material and the additional portion 22 of the tape extending beyond the normal edge of the tape resultant from the angle of fold is trimmed flush with the edge of the tape.

If double sided pressure sensitive tape which may be in the form of transfer tape, is used as the zipper tape adhering material, it is only necessary for the seamstress to press the folded over tape section to the main tape section to form the completed zipper. If heat sensitive vinyl tape is used, an iron will rapidly adhere the folded over tape section to the main tape section. If a spreadable adhesive is used, the tape sections will be held in contact until the adhesive sets up. Any other suitable means could likewise be used to secure the folded over tape section to the main tape section.

By folding over a section of the tape and adhering it to the main tape section the zipper is not only shortened to the desired length, but the folded edge 23 forms a stop for the slider at the upper end of the zipper. The zipper may thereafter be sewn into the garment along sewing line 24.

The above described technique envisions the shortening of a zipper in accordance with the length requirements of a particular application whereafter the zipper is installed in a garment in the usual manner. This requires the zipper to be carefully and accurately placed in the garment whereafter the zipper tape is baste stitched, usually by machine. As might be imagined, great accuracy and skill is required to properly align and hold the zipper during the baste stitching operation. Thereafter, the zipper is finally stitched in place. The utilization of the zipper tape adhering material for shortening of the zipper can be used for the dual purpose of also adhering the zipper to the garment prior to the final stitching operation thereby completely eliminating the baste stitch operation. A substantial and unexpected result is obtained since the skill in installing zippers resides not so much in proper placement of the zipper but in holding it in place while basting takes place. By eliminating the basting, the seamstress need only properly position the zipper whereby it is held in place by the adhering material for the final stitching operation. With such technique, zippers may be accurately and professionally installed by the amateur seamstress.

The foregoing technique is best understood in connection with FIGS. 6 through 9. FIG. 9 shows a roll of transfer tape 31 which consists of a backing or release paper 32 and a layer of adhesive material 33. Note that the width of the adhesive material is greater than that of the release paper for a purpose to be hereafter described. Transfer tape operates as follows. When a section of transfer tape is cut from roll 31 and the exposed side of

adhesive material 33 is applied to substantially any surface, it adheres thereto in pressure sensitive fashion. On gripping of the release paper, it may be stripped from the adhesive material thereby leaving the adhesive material deposited on the surface and exposing the theretofore concealed surface of adhesive material whereby an additional adhering function may be performed by the exposed adhesive material.

Referring to FIGS. 6 and 7, a length of transfer tape 31 is cut and placed over each tape section 14 with the adhesive material 33 in contact with the front side of the tape section. If desired, the zippers supplied in the zipper kit may have the transfer tape adhered thereto as shown in FIG. 6 or, the transfer tape may be supplied in the kit or separately as a roll such as that shown in FIG. 9.

As best shown in FIG. 7, release paper 32 is as wide or wider than the zipper tape section which it overlies while the adhesive material 33 is substantially narrower. This permits the edge of the release paper to be aligned with the teeth portion 15 of the zipper thus assuring that the adhesive material will be spaced outwardly from the teeth to prevent interference therewith. To use the zipper of FIGS. 6 and 7, the seamstress grasps and strips the release paper thereby exposing the adhesive material on the front side of the zipper tape. The zipper is carefully placed on the garment and, with slight pressure, the zipper adheres to the garment through the adhesive material thereby, in effect, basting the zipper to the garment. The seamstress need merely execute the final sewing operation to complete the installation.

The application of the adhesive material through the transfer tape also provides for the zipper shortening technique described above. As shown in FIG. 8, once the transfer tape has been applied to the zipper tape and the release paper stripped away, the adhesive material 33 is exposed. In order to shorten the zipper, prior to installation thereof in the garment, the seamstress need merely fold over the excess portion, preferably at the top of the zipper, to form a fold along a substantially 45° line 34 whereby the longitudinal axis of the folded portion will be substantially perpendicular to the longitudinal axis of the unfolded portion. The outer end is thus trimmed as indicated at trim line 35. When the top portion of each tape is folded over, the confronting faces having the adhesive material thereon adhere the tape in folded over position. Thereafter, the zipper is placed in the garment and "basted" by the remaining exposed portion of adhesive material. The final sewing operation locks the folded over portion of the zipper in place to effect a permanent shortening thereof. As described above, the folding of the tape provides for the top stops which are otherwise removed when the top of the zipper is cut off.

The zippers depicted in the drawings show both the standard metal teeth and the newer type of nylon coils and it is to be understood that the invention described herein is not limited to any particular type or construction of zipper, with the shortening and "basting" technique being equally suitable for zippers having metal teeth as well as those having nylon coils.

With the foregoing technique, a new article of commerce is created in the form of a zipper kit assembled as a unit to provide zippers of substantially every length for substantially every application. By providing zippers of various types of relatively long length together with an adhering material, the consumer has available an almost infinite variety of zipper lengths since the ultimate length of the zipper sewn into the garment is under the control of the consumer. With the technique, the seamstress can also speedily and accurately install the zippers supplied with the least possible difficulty while concurrently shortening the zipper if shortening is required on any particular application.

It will thus be seen that the objects set forth above, among those made apparent from the preceding description, are efficiently attained and, since certain changes may be made in the above construction without departing from the spirit and scope of the invention, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

What is claimed is:

1. A method of shortening a zipper having longitudinal zipper tapes comprising the steps of severing the top portion of the zipper tapes to leave a zipper having a length slightly longer than the require length, said excess length defining a foldable portion of zipper tape material, applying a zipper tape adhering material to one side of each zipper tape, folding said foldable portion at an angle to the longitudinal axis of the zipper tape from which the foldable portion extends and adhering said foldable portion to said zipper tape.

2. The method defined in claim 1 and further including the step of trimming each foldable portion substantially flush with the outside edge of the zipper tape to which it is adhered.

3. A method of shortening a zipper having longitudinal zipper tapes and adhering same to a garment comprising the steps of applying a transfer tape to the front face of each zipper tape along a substantial portion of the length thereof, said transfer tape including a release paper and an adhesive material to thereby deposit adhesive material on the zipper tapes, folding the top portion of each zipper tape at an angle to the longitudinal axis thereof to thereby shorten the zipper, and placing the zipper in a garment with the front face of said zipper tapes and the adhesive material in contact with the garment.

4. A zipper comprising a first zipper tape, a second zipper tape, a bottom stop joining said zipper tapes along abutting edges, zipper teeth extending from each abutting edge for the entire length of said zipper tapes from said bottom stop, a slider adapted to control meshing of said teeth, and top stops at the upper end of said zipper tape, each top stop comprising a portion of zipper tape folded on itself at an angle to the longitudinal axis of the zipper tape, and zipper tape adhering material securing said portion in folded position.

5. A method of adhering to a garment a zipper having longitudinal zipper tapes and zipper teeth extending from abutting edges of said zipper tapes, comprising the steps of locating one edge of a length of release tape ad-

jacent each line of zipper teeth with the release tape overlying the zipper tape from which the respective teeth extend and with adhesive material on the release tape facing the zipper tape front face, said adhesive material being spaced from said one edge to define a portion of release tape overlying said zipper tape adjacent zipper teeth which is free of adhesive material, pressing said release tape onto said zipper tapes to effect adherence of said adhesive material to said zipper tapes, stripping said release tape from said zipper tapes to leave deposited on said zipper tapes a quantity of adhesive material which, throughout its length, is spaced from the zipper teeth, placing the front face of the zipper in contact with a garment, and applying pressure to the rear face of the zipper to adhere the zipper to the garment.

6. As a new article of commerce, a zipper having longitudinal zipper tapes and zipper teeth extending from abutting edges of said zipper tapes, and a length of zipper adhering tape overlying each of said zipper tapes for adhering said zipper to a garment, each said length of zipper adhering tape comprising a release paper having first and second longitudinal edges, said first longitudinal edge located adjacent said zipper teeth, and an adhesive material on the surface of said release paper overlying said zipper tape, said adhesive material extending longitudinally of said release paper and having first and second longitudinal edges, said first and second longitudinal edges of said adhesive material being spaced from said first longitudinal edge of said release paper whereby to define an area of said release paper free of adhesive material adjacent said zipper teeth, said release paper being strippable from said adhesive material to leave said adhesive material adhered to said zipper tape and exposed for adhering said zipper to a garment when said release paper is stripped from the zipper tape.
